UNITED STATES PATENT OFFICE.

JACOB H. FLEISCH, OF NEW YORK, N. Y.

DESIGN FOR A NECKSCARF.

SPECIFICATION forming part of Design No. 12,714, dated January 31, 1882.

Application filed December 14, 1881. Term of patent 3½ years.

To all whom it may concern:

Be it known that I, JACOB H. FLEISCH, a citizen of the United States, residing in the city, county, and State of New York, have invented and produced a new and original Design for a Gentleman's Neckscarf, of which the following is a specification, reference being made to the accompanying drawing, forming part thereof.

10 The figure is a front elevation of a gentleman's neckscarf, illustrating my design.

Hitherto gentlemen's neckscarfs have been made the side edges of which, when the scarf was viewed at a front elevation, each presented an outline composed of two right lines meeting at an angle, or of a single curved line extending from the neck-line to the bottom of the scarf, or of a right line and a single curved line which meet or are joined into each other 20 on said edge.

The essential feature of my design is a notch or indentation formed in each of the side edges of a gentleman's neckscarf, substantially as shown in the drawing, and as hereinafter particularly described.

In the neckscarf shown in the drawing, A

is the center piece. B B are the aprons folded across said center piece. C is the upper or neck edge of the scarf, and D D are the side edges thereof. In each of the side edges of the scarf, as at E, are formed the notches or indentations shown. The edges of these notches may consist of curved lines which meet at the apex of the notch and have their convexities opposed to each other; or they may consist of right or irregular lines meeting at the apex aforesaid without changing the essential feature of my design, which consists of a gentleman's neckscarf having a notch or indentation formed in each of the side edges thereof, substantially as described.

What I claim as my invention, and desire to secure by Letters Patent, is—

The design for a gentleman's neckscarf herein shown and described, the same consisting of a neckscarf having a notch or indentation, E, in each of the side edges thereof.

JACOB H. FLEISCH.
